CLAIM

The ornamental design for a cutting tool, as shown and described.

DESCRIPTION

FIG. 1 is a front view of a cutting tool in accordance with an embodiment of the present design;

FIG. 2 is a rear view thereof;

FIG. 3 is a right side view thereof;

FIG. 4 is a left side view thereof;

FIG. 5 is a top view thereof;

FIG. 6 is a bottom view thereof;

FIG. 7 is a first perspective view thereof;

FIG. 8 is a second perspective view thereof;

FIG. 9 is a cross sectional view taken along line 9-9 of FIG. 1;

FIG. 10 is an enlarged view of 10 portion of FIG. 8;

FIG. 11 is an enlarged view of 11 portion of FIG. 9;

FIG. 12 is a cross sectional perspective view taken along line 12-12 of FIG. 1;

FIG. 13 is an enlarged view of 13 portion of FIG. 12; and, FIG. 14 is a referential view showing the state in use thereof. The broken lines in the drawings depict portions of the cutting tool and environmental subject matter which form no part of the claimed design.
